TREE HOLDER

Hiram M. Maxwell, 1748 N. Verdugo Road, Apt. 7,
Glendale, Calif. 91208

Filed May 6, 1968, Ser. No. 11,799

Term of patent 14 years

Int. Cl. D8—01, 03

U.S. Cl. D35—1

FIGURE 1 is a perspective view of a tree holder embodying my new design;

FIGURE 2 is an elevation view of the tree holder in the direction of line 2 of FIGURE 1;

FIGURE 3 is an end view of the tree holder;

FIGURE 4 is a plan view of the tree holder;

FIGURE 5 is a perspective view of the tree holder with a dotted line representation of a tree, two stakes, and an end guard for illustrative purposes, to enhance the clarity of the disclosure; and

FIGURE 6 is a plan view of the tree holder and its environment, taken along line 6—6 of FIGURE 5.

I claim:

The ornamental design for a tree holder, substantially as shown and described.
